Raymond M. Terry, 5560 Ascot Drive, Oakland, Calif.

Filed Oct. 20, 1959, Ser. No. 57,991

Term of patent 14 years

(Cl. D52—2)

Figure 1 is a perspective view of a coin operated newspaper sales rack or similar article, showing the front and left side, with the door partially open, embodying my new design; and

I claim:

The ornamental design for a coin operated newspaper sales rack or similar article, as shown.
